NOTCHING MECHANISM

John F. Peters, Leonia, N. J., assignor to American Can Company, New York, N. Y., a corporation of New Jersey

Application December 6, 1941, Serial No. 421,991

8 Claims.

(Cl. 164—50)

The present invention relates to a mechanism for notching sheet material and has particular reference to a rotary device for notching the sheets as they advance in a continuous procession.

In the manufacture of containers or cans made of metal or fibre, it is customary to form notches and to cut off the corners of flat blanks from which the bodies and other parts of the cans are made to produce better fit or to reduce the thickness of the can seam at predetermined places.

The instant invention contemplates a notching mechanism for notching such sheets at high speed and while the blanks are moving in a continuous procession.

An object therefore of the invention is the provision of a notching mechanism wherein sheets of material are notched as they are advanced along a predetermined path of travel at high speed and in an orderly spaced continuous procession so that increased production may be obtained.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a notching mechanism embodying the instant invention, with parts broken away;

Fig. 2 is a transverse sectional view taken substantially along the broken line 2—2 in Fig. 1, with parts broken away;

Fig. 3 is a horizontal sectional view taken substantially along the line 3—3 in Fig. 2, with parts broken away; and

Figs. 4, 5 and 6 are schematic views showing the relation of a notching tool to the sheets being notched, the views showing different positions of the tool incident to performing the notching operation.

As a preferred embodiment of the instant invention the drawings illustrate a mechanism for notching fibre can body blanks A by cutting off corner pieces B from the side seam edges of the blanks to produce clipped or beveled edges C thereon, although the invention is equally well adapted for cutting other forms of notches and for other kinds of material, such as metallic or non-fibrous materials from which containers are made.

The blanks A to be notched are advanced along a straight path of travel in spaced and timed

order and in a continuously moving procession while being supported on a horizontal table 11. The table is or may be formed as an integral part of a frame 12 which may be the main frame of a more elaborate machine. The blanks are guided along the table by a pair of spaced and parallel guide rails 14 which are formed at the outer edges of the table.

The blanks A are propelled over the table by a plurality of sets of upper and lower continuously rotating rollers 16 which are spaced at intervals along the table. These rollers preferably are formed with a metallic hub 17 (Fig. 2) and a metallic outer shell 18 with a resilient core 19 made of rubber interposed between the hub and the shell. Such a roller may be set on a fixed axis and yet be capable of yieldably pressing down on the blank for frictionally advancing it over the table.

The lower roller 16 in each set is located in a recess 21 cut in the table, with the top of the roller flush with the top of the table. This roller is mounted on a shaft 22 journaled in bearings 23 which depend from the table and in a bearing 24 formed in the main frame. The lower roller shafts may be rotated in unison in any suitable manner operating in time with the other moving parts of the mechanism.

The upper rollers 16 of each set are located above the table and normally engage the lower rollers. These upper rollers are mounted on shafts 26 which are journaled in bearings 27 formed in an overhanging bracket 28 bolted to the outside of the main frame 12. The upper roller shafts extend beyond the bracket and carry spur gears 31 which mesh with and which are driven by gears 32 mounted on the lower roller shafts 22.

In this manner the upper and lower feed rollers are rotated in unison. The spacing of the rollers along the table is such that at least one set of rollers is always in contact with each blank as it advances between them and along the table.

While the blanks A are thus fed over the table 11 in a continuous procession, the corner pieces B at one edge of each blank are notched out. This notching operation is effected by a rotary notching device which is located adjacent a clearance recess 35 formed in the table 11.

The notching device includes a rotatable horizontal notcher disc 36 (Figs. 1 and 2) formed on a concentric depending stem 37 which is journaled in a vertical bearing block 38. The bearing block is formed with a cylindrical shouldered shank 39 which is mounted in a horizontal cam

plate 41 secured to a ring bracket 42 bolted to the main frame. The bearing block is held against rotation by a key 43 and is retained against vertical displacement by a locknut 44 which is threaded onto the lower end of the shank 39.

The notcher disc stem 37 extends down below the bearing block shank 39 and carries a bevel gear 47 which meshes with and is driven by a bevel pinion 48. The pinion is mounted on a horizontal driving shaft 49 which is journaled in a bearing 51 in the ring bracket 42 and in a bearing 52 in the main frame. This driving shaft is rotated in any suitable manner in time with the feed roller shafts 22, 26 so that the peripheral speed of the rotating disc 36 will be equal to the lineal speed of the blanks advancing along the table 11.

The rotating notcher disc 36 carries a plurality of notching heads 55. There are three such heads shown in the drawings and they are equally spaced and are disposed adjacent the periphery of the disc. Each notching head 55 includes a vertically movable notching tool 56 of trapezoidal cross section (see Figs. 4, 5 and 6) which cooperates with a nonrotatable die 57 (Figs. 1 and 2) having a die recess 58.

Each of the notching dies 57 is secured by screws 61 (Fig. 2) in a head bracket 62 which is disposed on top of the notcher disc 36. The top surface of each die is flush with the top of the table 11 and is formed with beveled corners 63 which permit the die to move under and in engagement with the blanks for the notching operation, as will be fully explained hereinafter.

Each of the notching head brackets 62 are formed with a depending sleeve 65 which is carried in a vertical bearing 66 formed on the notcher disc 36. The sleeve of each bracket extends down below the bearings 66 and carries a cam arm 67 (see also Fig. 3) having a cam roller 68 which operates in a cam groove 69 formed in the cam plate 41. This cam action rocks the notching head brackets 62 slightly as they are carried around by the notcher disc 36.

Each of the notching tools 56 is formed on a block 71 (Figs. 1 and 2) which is secured by a bolt 72 to a vertical slide 73 disposed in a dovetail slideway 74 formed in the associated head bracket 62. The slide extends down through the die recess 58 and into a head recess 76 formed in the notching head. In this head recess the lower end of the slide is formed with a T slot 77 which forms a swivel joint for a T shaped knob 78 on a slide actuating rod 79. There is one of these slides and actuating rods for each notching head 55.

The slide actuating rods 79 extend down through the head sleeves 65 and adjacent their lower ends carry cam rollers 83 which are mounted on pivot pins 84 secured in the rods. The pivot pins extend through slots 85 formed in opposite sides of the head sleeves 65. The cam rollers operate in a cam groove 86 formed in a cam 87 which surrounds and is integral with the notcher disc stem bearing block 38. This cam is designed to move each notching tool 56 up and down relative to its die 57 as the notcher disc 36 rotates.

Since the die 57 and slide 73 which carries the tool 56 are supported in the head bracket 62 for each notching device, the tool always remains in vertical alignment with the die recess 58 in its cooperating die 57.

Hence as the notching disc 36 rotates it brings

the notching heads 55 individually and one after the other into notching position adjacent the table 11 along which the blanks to be notched are advancing. The timing is such that a notching head 55 comes into position just as a space between two adjacent blanks A is passing the notching station. With this timing, as a notching head approaches the table 11, the notching die 57, passing along through the arc of the rotating notcher disc 36, moves into the table recess 35 and under and in engagement with the bottom surface of the advancing blanks A as shown by the position of the tool 56 in Fig. 4. The notching tool 56 is disposed directly above the moving blanks.

As the notching die 57 thus swings into position adjacent the moving blanks, the cam roller 68 traversing the cam groove 69 in the cam plate 41, rocks the head sleeve 65 and its attached head bracket 62 slightly on their common center to bring the die 57 and the tool 56 into parallelism with the longitudinal or side seam edge of the passing blank. The die and the tool are maintained in this parallel position relative to the moving blanks as the notching head moves through an arc adjacent the path of travel of the blanks.

When the moving notching head 55 is exactly in a position which is normal to the path of travel of the blanks along the table, the die 57 and tool 56 overlap the two adjacent transverse edges of adjacent blanks on the table as best shown in Figs. 1 and 5. At this time the cam roller 83 traversing the cam groove 86 operates to draw the slide 73 down in a quick movement thus passing the notching tool 56 through the advancing blanks A and into the die recess 58. This constitutes the notching operation at which time the corner portions B of the two adjacent blanks are cut off. This is done at great speed and while the notching head and the blanks are in continuous motion.

The cut off portions B of the blanks fall down through the die recess 58. To prevent clogging of the die, all its exterior surfaces are disposed at outwardly and downwardly extending angles so that the cut off portions B will readily slide off the die to any suitable place of deposit.

After the notching operation and while the die 57 and the tool 56 are still in parallelism with the blank edges, the tool is moved by its control cam 87 up out of the die recess 58 to its original normal position. When the tool is clear of the moving blanks, the notching head is rocked back into its original position in readiness for the next notching operation when the head is again moved in a rotary path adjacent the table 11.

In this manner the die 57 and the tool 56 are moved away from the blanks while maintaining a proper relation with the blanks so that no damaging interference results. Thus as the blanks advance past the notching station in a continuous orderly procession, the notcher disc 36 in its continuous rotation brings the proper notching head 55 into position to effect the notching of the blanks with great rapidity.

It is thought that the invention and many of its attendant advantages will be understood from the foregoing description, and it will be apparent that various changes may be made in the form, construction and arrangement of the parts without departing from the spirit and scope of the invention or sacrificing all of its material ad-

vantages, the form hereinbefore described being merely a preferred embodiment thereof.

I claim:

1. A sheet notching mechanism, comprising in combination, means for continuously advancing sheets in spaced processional order along a predetermined path of travel, a continuously rotating member disposed in tangential relation to and in the plane of the advancing sheets, and a notching instrumentality carried by said rotating member and engageable with a sheet as the latter moves adjacent said notching instrumentality for cutting a notch in said sheet.

2. A sheet notching mechanism, comprising in combination, means for continuously advancing sheets in spaced processional order along a predetermined path of travel, a continuously rotating member disposed in tangential relation to and in the plane of the advancing sheets and operating in time with such travel, and a notching instrumentality carried on said rotating member and simultaneously engageable with portions of two adjacent sheets as they move adjacent said instrumentality for cutting notches in both of said sheets.

3. A sheet notching mechanism, comprising in combination, means for continuously advancing sheets in spaced processional order along a predetermined path of travel, a continuously rotating member disposed adjacent an edge of the moving sheets and rotating in time with the sheets, a notcher head mounted on said member, a die instrumentality carried in said notcher head and engageable under and with a moving sheet as said rotating member brings the notcher head adjacent, and a notching tool also carried in said notcher head and movable into said die instrumentality whereby a notching operation is performed on said moving sheet as said rotating member passes the head into notching position.

4. A sheet notching mechanism, comprising in combination, means for continuously advancing sheets in spaced processional order along a predetermined path of travel, a continuously rotating member disposed adjacent an edge of the moving sheets and rotating in time with the sheets, a notcher head mounted on said member, a die instrumentality carried in said notcher head and engageable with portions of two adjacent moving sheets as said rotating member brings the notcher head adjacent, and a notching tool also carried in said notcher head and movable into said die instrumentality whereby a notching operation is performed on said moving sheets as said rotating member passes the head into notching position.

5. A sheet notching mechanism, comprising in combination, means for continuously advancing sheets in spaced processional order along a predetermined path of travel, a continuously rotating member disposed adjacent an edge of the moving sheets and rotating in time with the sheets, a plurality of notcher heads arranged in spaced order adjacent the periphery of said rotating member and movable in succession into notch-

ing position adjacent the moving sheets, a die instrumentality carried in each of said heads and engageable under and with a sheet as its head comes into position adjacent, and a notching tool also carried in each head in spaced relation to its die instrumentality whereby cooperation between said notching tool and said die instrumentality effects a notching operation on said sheet as the head comes adjacent.

10 6. A sheet notching mechanism, comprising in combination, means for continuously advancing sheets in spaced processional order along a predetermined path of travel, a continuously rotating member disposed adjacent an edge of the moving sheets and rotating in time with the sheets, a notcher head mounted on said member, a die instrumentality carried in said notcher head and engageable under and with a moving sheet as the rotating member brings the notcher head adjacent, a notching tool also carried in said notcher head and movable into said die instrumentality, and actuating means for shifting said notcher head to bring said die instrumentality into parallelism with the path of travel of the sheets whereby the notching operation is performed by said tool entering said die instrumentality as the head comes into position adjacent the sheets.

30 7. A sheet notching mechanism, comprising in combination, a table for supporting sheets to be notched, a plurality of sets of cooperating upper and lower feed rollers for continuously advancing sheets in spaced processional order along said table, adjacent sets of rollers being spaced apart 35 a distance less than the width of a sheet, a continuously rotating member disposed adjacent said table, and a notching instrumentality carried on said rotating member and engageable with a sheet advancing over said table for performing a notching operation on the moving sheet.

8. A sheet notching mechanism, comprising in combination, a table for supporting sheets to be notched, a plurality of sets of cooperating upper and lower yieldable feed rollers for continuously advancing sheets in spaced processional order along said table, said table having a recess along one edge thereof, guide rails located on said table for guiding said sheets, a horizontal continuously rotating member disposed adjacent said table recess, means for rotating said member in time with said feed rollers, a notcher head mounted on and projecting up from said member and movable into the table recess by rotation of said member, a die instrumentality carried in said notcher head and movable under an edge of a sheet advancing along said table when said head moves into said table recess, a notching tool disposed above said die instrumentality and vertically slideable in said head, and cam means for moving said tool down through an advancing sheet and into said die instrumentality when the head moves into said table recess whereby a notching operation is performed on said moving sheet.

JOHN F. PETERS.
